tion of Pennsylvania

Application November 27, 1943, Serial No. 512,016

18 Claims.

(Cl. 66—109)

This invention relates to a straight or full-fashioned knitting machine, and to a novel and improved bearing structure for certain of its mechanisms, such as the knockover bit mechanisms.

The knockover bit device or mechanism of each knitting section of a straight or full-fashioned knitting machine is cooperatively associated with a sinker-head device or mechanism. The knockover bits move in unison and catch the thread as it is dropped from the noses of the sinkers and dividers when they are pulled back by the catch-bar. In this manner the last knitted loops are held in position while the needles move downward to pull the thread through the old loops. Precise location and operating movement of the knockover bits relative to the sinkers, dividers and other knitting elements, is important to the production of a fabric with perfect loop formation. In full-fashioned hosiery knitting machines of the type known as "Reading" machines, the knockover bits are secured for united movement in a brass bed, or bar, provided with integral end trunnions mounted for rotary oscillating movements in stationary bearings on the sinker head. When the trunnions become worn the said precise location and operation of the knockover bits is disturbed and since no adjustment is possible to overcome this difficulty it has heretofore been necessary to incur the expense and trouble of removing the bar and refinishing its said trunnions, or in certain cases of replacing the entire knockover bit bar with one having perfect trunnions. Longitudinal adjustment of the knockover bits relative to certain knitting elements is also essential from time to time. The present construction and arrangement of the parts involved make this a procedure requiring considerable skill and time. The indicated expenses and difficulties are more serious in the finer gauge machines, such as 51 gauge full-fashioned hosiery knitting machines, and in view of the trend toward the more extensive use of such type of machines, and for other reasons, the provision of means for correcting the indicated and similar conditions has become highly desirable and important from the standpoint of the machine users and operators.

One object of my invention is to provide a straight or full-fashioned knitting machine having novel means for eliminating, or minimizing, the indicated and other expenses and difficulties.

Another object is to provide such a machine having novel means for facilitating the making of positional adjustments of the knockover bits

relative to certain cooperating knitting elements.

Another object is to provide a novel bearing structure for association with a straight knitting machine device or mechanism, such as a knockover bit mechanism, arranged to facilitate the precise positioning of one or more of its operating parts relative to one or more operating parts of a cooperating device or mechanism, such as a sinker-head mechanism.

10 A further object is to provide such a structure which can be readily embodied in new machines, or utilized as a repair or substitute means in old machines, to impart thereto certain structural and functional advantages.

15 An additional object is to provide such a structure having novel positive means for maintaining the movable elements of certain coacting straight knitting machine devices in determined relation.

20 A still further object is to provide such a structure having novel means to facilitate the lubrication and replacement of certain parts thereof which are subject to wear.

25 Another object is to provide such a structure which can be utilized for repairing and improving a defective straight knitting machine device or unit, such as the knockover bit unit thereof, without necessitating the replacement of the main or most expensive part thereof, such as the knockover bit bed, or bar.

30 Another object is the provision of such a structure in association with the sinker-head and knockover bit assembly of a straight or full-fashioned knitting machine, so as to impart to the same, as well as to the machine in which it is mounted, the referred to and other structural and functional features of advantage.

35 With these and other objects in view, which will become apparent from the following detailed description of certain practical and illustrative embodiments of my novel improvements, shown in the accompanying drawings, my invention comprises the novel elements, features of construction and arrangement of parts in cooperative relationship, as hereinafter more specifically pointed out in the claims.

40 In the drawings:

Figure 1 is a plan view of certain parts of a standard sinker-head and cooperatively associated knockover bit unit of a conventional straight or full-fashioned knitting machine, having my invention applied thereto.

45 Fig. 2 is a front elevational view of the mechanism shown in Figure 1.

Fig. 3 is a left end elevational view of the mechanism shown in Figs. 1 and 2, with certain

additional correlated standard knitting machine parts indicated in dot-and-dash lines.

Fig. 4 is an enlarged partial sectional view through certain parts of the bearing structure of my invention, taken substantially as indicated by the arrows 4-4 on Fig. 1.

Fig. 5 is a plan view of the knockover bit bed, or bar forming part of my invention, and indicates in dot-and-dash lines the parts of a standard knockover bit bar which are removed or cut away at its ends to enable its utilization in conjunction with the improved bearing construction of my invention when the latter is provided as a repair unit.

Fig. 6 is a left end elevational view of Fig. 5.

Fig. 7 is a cross-sectional view taken substantially as indicated by the arrows 7-7 on Fig. 4.

Fig. 8 is a side elevational view of a bearing rod forming part of my invention.

Fig. 9 is an end elevational view of the rod shown in Fig. 8.

Fig. 10 is an enlarged detail sectional view taken substantially as indicated by the arrows 10-10 on Fig. 2.

Fig. 11 is a side elevational view of one of the bearing elements or sleeves forming part of my novel bearing structure, and

Fig. 12 is an end elevational view of the element shown in Fig. 11.

For illustrative purposes, a practical form of the novel bearing structure of my invention is herein shown and described in association with the sinker-head and knockover bit mechanisms of a conventional straight or full-fashioned hosiery knitting machine of the type known as a "Reading" machine. As the description proceeds, it will be realized that the construction and arrangement disclosed can be readily associated with the said mechanisms of new machines of this type, or similar machines already in use. When associated with a new machine, certain parts of my invention are provided in standardized form best suited to accomplish their intended purpose. When associated with a machine already in use, the invention is necessarily applied as a substitute means for the old bearing structure which it displaces, and as such will not only impart to such a machine its inherent advantages but in addition will make possible the re-utilization of certain machine parts which would ordinarily have to be discarded. In the latter case, certain of the standard parts of the mechanism in use, by modification, are also converted into component elements of my invention. It is to be understood, therefore, that my invention can be variously applied to straight or full-fashioned knitting machines, in standardized form, or in a form consisting partly of new, and partly of old modified machine elements.

To facilitate an understanding of the various phases of my novel bearing structure, the said sinker-head and knockover bit mechanisms with which it is cooperatively associated, will first be briefly described.

In Figs. 1, 2 and 3 there is shown a sinker-head 15 of the usual and well known type associated with each fabric blank knitting section of a conventional straight or full-fashioned knitting machine. Such a device, or mechanism, generally comprises a stationary sinker-head support 16, a sinker-head bottom 17, a sinker-head top 18, a verge plate 19 provided with a cushion element 20, a presser edge 21, sinkers 22 and dividers 23. For purposes of orientation of these sinker-head parts in the knitting machine, Fig. 3 indicates in

dot-and-dash lines such additional machine parts as the needles 24, needle bed 25, needle clamp 26 and needle bar 27.

The sinkers 22 and dividers 23 are mounted in parallel slots milled in the sinker-head bottom 17 and top 18, which slots serve as guides for the sinkers and dividers when they are moved back and forth by the usual jacks and catchbar, not shown.

Each standard sinker-head of the machine has cooperatively associated therewith a brass knockover bit support or bed 28, having fixedly clamped thereto a multiplicity of knockover bits 29, corresponding in number with the sinkers and dividers. During the knitting operation, the knockover bits serve to catch the thread as it is dropped from the noses of the sinkers and dividers when they are pulled back by the catchbar. In this manner the last knitted loops are held in position by the knockover bits while the needles move downward and pull the thread through the old loops and then start their upward travel toward their original position, or starting point. During this procedure, the knockover bits jointly carry out their usual oscillating movement which is regulated in accordance with the thickness of the yarn being knitted. To enable the knockover bits to carry out the said oscillating movement, the standard brass knockover bit support, or bed, of the said "Reading" type machines, is provided with integral end trunnions which are mounted in split bearings united with the sinker-head, and the wearing action which takes place between the trunnions and bearings results in certain of the above indicated difficulties and expenses.

In accordance with my invention, the knockover bit mounting or bed 28 differs from one of the referred to standard mountings in that the ends thereof are devoid of the usual trunnions, and terminate just beyond the last or end knockover bits 29. A certain bottom section of the said standard bar is also omitted. To make the difference entirely clear, Figs. 5 and 6 indicate in dot-and-dash lines the integral end trunnions and associated parts, as well as the said bottom section of a standard knockover bit bed or mounting which are omitted, or cut off (when converting said standard bar), to provide a knockover bit mounting in accordance with my invention.

Further in accordance with my invention, there is provided a bearing rod 30, having a cut-out part 31 against the flat surface of which is secured the knockover bit bed 28, by means of screws 32 which pass through apertures in the bed 28 and are secured in the threaded bores 33 of the rod 30.

The ends of the rod 30 are mounted for rotary movement in two similar bearing members or sleeves 34, each of which is provided with an end flange 34^a, and a longitudinally extending oil aperture 34^b. The sleeves 34 are mounted in centrally split clamp devices 35 on depending members 36 integral with the sinker-head bottom 17. The sleeves 34 are arranged so that their flanges 34^a are secured in opposed relationship in the clamp devices 35 and in contact with the ends of the knockover bit bed 28, as clearly shown in Fig. 4. The sleeves 34 are positioned in the clamp devices 35 so that their oil apertures 34^b are in registry with circular oil holes 35^c of the clamp devices as shown in Fig. 10. Each of the centrally split clamp devices 35 consists of two complementary parts or jaw elements 35^c and 35^d. The element 35^c is formed on the depending

member 36, and the separate part 35^d is held in cooperating position with the part 35^c by means of screws 38 which pass through apertures in the separate part 35^d and are engaged in coextensive threaded apertures of the element 35^c.

Loosening of the screws 38 will effect release of the gripping action exerted by the clamp devices 35 on their respective bearing sleeve 34, and will permit longitudinal sliding movement of the latter within the complementary jaws, or bore-like substantially circular aperture of each of the said clamp devices.

To prevent the elongated oil apertures 34^b from moving out of registry, or becoming displaced, relative to their respective circular oil holes 35^b, the bearing sleeves 34 and clamp devices 35 are provided with means to maintain them in the relationship shown in Fig. 3, or substantially so. One form of such means is illustrated in the drawings and comprises the provision of diametrically opposed flat portions 34^c on the sleeves 34 in conjunction with clamp devices 35, the complementary jaw elements 35^c and 35^d of which have arcuate sleeve holding portions of a smaller radius than the radius of the external surface of the sleeves 34. By referring to Fig. 3, it will be apparent that with this arrangement the outside peripheries of the sleeves 34 are more particularly contacted by the arcuate sleeve holding portions of the clamp jaws adjacent to the corners formed by the flat portions 34^c, and that the interfitting relationship of the sleeves 34 and clamp devices 35 is consequently such as to prevent any substantial rotary movement of the sleeves 34 within the clamp jaws 35^c and 35^d, unless the latter are separated to an extent beyond that necessary to effect free longitudinal adjustment of the sleeves 34 for the purposes previously explained.

When it is desired to move the knockover bit bed 28 longitudinally, so as to effect precise positioning of the knockover bits 29, relative to such parts as the sinkers 22, dividers 23, or needles 24, it is merely necessary to somewhat loosen the screws 38, so that the sleeves 34 will be free to slide in the clamp devices 35. The bed 28 and its therewith united bearing rod 30 can then be moved lengthwise to any selected position of adjustment. To maintain the bed 28 in a determined longitudinally adjusted position, the sleeves 34 are moved toward the bed 28 until the flanges 34^a are in contact with the ends of the latter (see Fig. 4), after which the sleeves are fixed in position by again tightening the screws 38. In this manner the knockover bit bed 28 is contactingly arranged between the fixed bearing elements 34 in such manner that the bed can readily carry out its usual rotary oscillating movements but is positively confined intermediate the elements 34 against longitudinal movement or displacement in either direction.

From Figs. 3 and 10, it will be clear that the oil apertures 34^b of the sleeves 34 will be in registry with the oil holes 35^b during and after the indicated adjustments, so that the parts of the rod 30 which are mounted for oscillatory movement in the sleeves 34 can be oiled at all times.

The rod 30 has connected thereto a motion transmitting member 40 which in turn is actuated in usual manner by the means provided in a standard knitting machine to impart rotary oscillating, or rocking movement, to the knockover bits in well-known manner.

It is to be particularly noted that when the bearing structure of my invention is provided as

standard equipment for new straight or full-fashioned knitting machines, the parts thereof such as the knockover bit bed 28 can be made of brass, as usual, or of some other suitable metal or material, since its construction does not include any integral elements which are subject to operating wear, as in the case of the trunnions above explained. Also, that the rod 30, and bearing sleeves 34 can be readily replaced when worn or impaired, so that the same can be made of relatively low cost and serviceable material, such as steel, plastic material, or the like, considered suitable for this purpose.

Since the ordinary knockover bit bearing structure of a straight or full-fashioned knitting machine includes a pair of split bearings which are similar to the clamp devices 35, except that the bearing bore or aperture thereof is of smaller diameter so as to accommodate the previously referred to integral trunnions of a standard knockover bit bed, it will be understood that such split bearings can be readily converted into the clamp devices of my invention when the latter is substituted in a machine of this type, by simply enlarging the diameter of the bearing bores to accommodate therein the sleeves 34, as previously explained and clearly shown in the drawings.

Of course, the improvements specifically described, by which the noted results are obtained, can be changed and modified in various ways without departing from the invention herein disclosed and more particularly defined by the appended claims.

I claim:

1. A straight knitting machine comprising a sinker-head, a knockover bit unit cooperatively associated with said sinker-head and including supporting means arranged in fixed position relative to the sinker-head, two bearing elements removably secured in determined position on said supporting means, and a mounting provided with knockover bits and detachably secured means arranged for rotary movement in said bearing elements.

2. A straight knitting machine comprising a sinker-head, a knockover bit unit cooperatively associated with said sinker-head and including supporting means arranged in fixed position relative to the sinker-head, two bearings associated with said supporting means, a device provided with knockover bits, and a rod detachably secured to said device having portions thereof mounted for rotary movement in said bearings.

3. In a straight knitting machine the combination with a machine device, of a cooperating unit comprising supporting means arranged in fixed relation to said device, two bearing sleeves, means for selectively securing said sleeves to the supporting means in relatively spaced position, means associated with said device having parts arranged in intermediate contacting relation with said sleeves, and a member detachably secured to said last mentioned means and provided with portions mounted for rotary movement in said sleeves.

4. In a straight knitting machine the combination with a machine device, of a cooperating unit comprising supporting means arranged in fixed relation to said device, two bearing sleeves, means for selectively securing said sleeves to the supporting means in relatively spaced position, movable means associated with said device having parts arranged in intermediate contacting relation with said sleeves, and a member detach-

ably secured to said movable means and provided with portions mounted for rotary movement in said sleeves.

5. In combination, a sinker-head having united therewith two spaced clamp devices, a separate bearing element secured in position by each of said devices, a rod having portions thereof mounted for rotary movement in said elements, a knockover bit support secured to said rod intermediate the elements, and means arranged to prevent longitudinal movement of the support relative to said elements.

6. In combination, a sinker-head having united therewith two spaced split clamp devices, screw means arranged to loosen and tighten said devices, a separate bearing element secured in position by each of said devices, a rod having portions thereof mounted for rotary movement in said elements, a knockover bit support secured to said rod intermediate the elements, and means arranged to prevent longitudinal movement of the support relative to said elements.

7. In combination, a sinker-head having united therewith two spaced depending members provided with axially aligned bores, a separate bearing sleeve slidably engageable in the bore of each member, means arranged to secure said sleeves in longitudinally determined position in said bores, a rod having portions thereof mounted for rotary movement in said sleeves, a knockover bit support secured to said rod intermediate the sleeves, and means arranged to prevent longitudinal movement of the support relative to the sleeves.

8. In combination, a sinker-head having united therewith two spaced depending members provided with axially aligned bores, a separate bearing sleeve slidably engageable in the bore of each member, means arranged to secure said sleeves in longitudinally determined position in said bores, a rod having portions thereof mounted for rotary movement in said sleeves and provided intermediate said portions with a flat surface, a knockover bit support secured to said flat surface, and means arranged to prevent longitudinal movement of the support relative to the sleeves.

9. In combination, a sinker-head having united therewith two spaced depending members each provided with a bore and an oil hole extending through a wall portion to the bore, a separate bearing sleeve slidably engageable in the bore of each member and provided with a lengthwise extending oil aperture arranged to register with the oil hole of the respective member with which the sleeve is slidably engaged, means arranged to secure said sleeves in longitudinally determined position in said bores, a rod having portions thereof mounted for rotary movement in said sleeves, a knockover bit support secured to said rod intermediate the sleeves, and means arranged to prevent longitudinal movement of the support relative to the sleeves.

10. In combination, a sinker-head having united therewith two spaced clamp devices, a separate bearing element secured in position by each of said devices, a rod having portions thereof mounted for rotary movement in said elements, and a knockover bit support secured to said rod in intermediate contacting relation with said elements.

11. In combination, a sinker-head having united therewith two spaced clamp devices, two separate bearing sleeves each having a flange at one end and secured in position by one of said

devices so that the flanges are arranged in opposed relationship, a rod having portions thereof mounted for rotary movement in said sleeves, and a knockover bit support secured to said rod in intermediate contacting relation with said flanges.

12. In combination, a sinker-head having united therewith two spaced depending members provided with aligned clamp devices each of which has an oil hole extending through a wall portion thereof, a separate bearing sleeve secured in each of said devices which sleeves are each provided with a lengthwise extending oil aperture in registry with the oil hole of its respective clamp device, a rod having portions thereof mounted for rotary oscillation in said sleeves and provided intermediate said portions with a flat surface section, a knockover bit support secured to said section, means arranged to prevent longitudinal movement of the support relative to said sleeves, and means associated with said rod for imparting rotary movement thereto.

13. A straight knitting machine comprising a sinker-head, two aligned clamp devices united with said sinker-head, a separate bearing sleeve secured in each of said devices, a rod having portions mounted for rotary movement in said sleeves, a support secured to said rod, knockover bits united with said support, and means arranged to prevent longitudinal movement of the support relative to the sleeves.

14. A straight knitting machine comprising a sinker-head having united therewith two spaced depending members provided with axially aligned bores, a separate bearing sleeve in the bore of each member, means arranged to secure said sleeves in longitudinally determined position in said bores, a rod having portions mounted for rotary oscillation in said sleeves, a support secured to said rod, knockover bits united with said support, and means arranged to prevent longitudinal movement of the support relative to the sleeves.

15. A straight knitting machine comprising a sinker-head, a knockover bit unit cooperatively associated with said sinker-head and including two bearing elements, means arranged to secure said elements in determined position relative to the sinker-head, a rod having portions thereof mounted for rotary movement in said elements, a support secured to said rod, knockover bits united with said support, and means arranged to prevent longitudinal movement of the support relative to the elements.

16. A straight knitting machine comprising a sinker-head, a knockover bit unit cooperatively associated with said sinker-head and including two bearing sleeves, means arranged to secure said sleeves in determined position relative to the sinker-head, a rod having portions thereof mounted for rotary movement in said sleeves, a support secured to said rod, knockover bits united with said support, and means arranged to prevent longitudinal movement of the support relative to the sleeves.

17. A straight knitting machine comprising a sinker-head, a knockover bit unit cooperatively associated with said sinker-head and including two bearing sleeves, means arranged to secure said sleeves in determined position relative to the sinker-head, means adapted to permit longitudinal adjustment of the sleeves, a rod having portions thereof mounted for rotary movement in said sleeves, a support secured to said rod, knockover bits united with said support, and

means arranged to prevent longitudinal movement of the support relative to the sleeves.

18. A straight knitting machine comprising a sinker-head, a knockover bit unit cooperatively associated with said sinker-head and including two bearing sleeves, means arranged to secure said sleeves in determined position relative to the sinker-head, means adapted to permit individual

longitudinal adjustment of the sleeves, a rod having portions thereof mounted for rotary movement in said sleeves, a support secured to said rod, knockover bits united with said support, and means arranged to prevent longitudinal movement of the support relative to the sleeves.

FRANK G. WEISBECKER.
